PUMP

Beryl A. Edwards and Bayard G. Duer, Decatur,
Ill., assignors to Zephyr-Wayne Company, De-
catur, Ill., a partnership

Application October 1, 1943, Serial No. 504,608

4 Claims. (Cl. 103—111)

This invention relates to apparatus such as rotary pumps of the type comprising a rotor and stator having opposed faces, the rotor face being provided with a circular series of blades and the stator face with a raceway or raceways registering with the blades and provided with inlet and outlet ports. A main object of the invention is to provide an effective seal between the faces whereby the efficiency of the apparatus is enhanced. Another object is to provide a construction facilitating assembly. The invention is shown in a practical embodiment, by way of illustration, in the accompanying drawings, in which:

Figure 1 is a side elevation of a motor and pump unit in accordance with the invention.

Figure 2 is a vertical axial section of the pump with a raceway section substantially on line 2—2 of Figure 3.

Figure 3 is an end view of the pump, with parts broken away, as seen from the right of Figure 1.

Figure 4 is a face view of the pump rotor.

Figure 5 is a partial face view of the pump stator.

Figure 6 is an enlargement of a portion appearing in Figure 2 and including a sealing member in accordance with the invention, and

Figures 7 to 10 are views similar to that of Figure 6, but showing sealing members in different form or arrangement.

Referring to the drawings and first to Figures 1 to 6, reference numeral 15, Figure 1, designates a base on which is mounted an electric motor 16 and a pump 17 constructed in accordance with the invention. The armature shaft 18 of the motor is in driving connection with the pump shaft 19 through a coupling 20.

The pump 17 comprises a casing 21 provided with a bottom flange 22 which is bolted to the base 15. The casing carries the shaft 19 in an end bearing 24, Figure 1, and in an inner bearing 25, Figure 2, mounted in a vertical partition, not shown, in an interior cavity 23, Figure 2. Adjacent the right-hand end of the casing the pump interior has a further vertical partition 26 providing a stuffing box 27 through which the shaft 19 extends. Outwardly of the partition 26 is a cavity 27 bounded by a peripheral wall 28 and open to the right. Within this cavity is disposed a rotor 29 which is fixed on the shaft 19.

The rotor has a peripheral portion 30 having plane faces 31 and 32 outwardly and inwardly of a concentric circular groove 33 in which is mounted a multiplicity of blades 34 in known manner. The stator 35 has plane faces 36 and 37 opposed to the rotor faces 31 and 32, and between these

stator faces is a pair of arcuate raceways 38 and 39, Figure 3, which register with the rotor groove 33. The outer portion of the stator abuts the outer end of the peripheral wall 28 and is secured in position by screws 40 and 41, Figure 3. Inwardly of the face 37 the stator includes an imperforate central web 42 so that the stator closes the cavity 27. On its outer side the stator includes a closed wall formation 43 which terminates in a circular intake neck 44 which is coaxial with the rotor, this wall formation, including opposite hollow extensions 45 and 46 in communication with inlet ports 47 and 48. Outwardly of the wall formation 43 the stator is provided with outlet ports 49 and 50, Figures 3 and 5.

Reference numeral 51, Figures 1, 2, and 3, designates a cap which is bolted to the end of the casing to close the same. The cap has a top threaded opening 52 in which is engaged an inlet pipe 53, and below the opening 52 is a chamber or passage 54 provided with a lateral mouth 55 engaged around the neck 44 and compressing a sealing gasket 56. Opposite the mouth 55 the cap has a threaded opening 57 for a vacuum gauge V. The fluid delivered by pipe 53 is guided by the chamber 54 to the stator cavity and the inlet ports 47 and 48. An outlet chamber 58 is defined between the cap and the stator and at its upper end is in connection with a passage 59 in the casing 21 which has a threaded outlet opening 60 in connection with a discharge pipe 61. A threaded opening 62 communicates with the passage 59 and receives a pressure gauge P.

Formed in the face 31 of the rotor concentrically with the axis is a groove 63 which has concentric cylindrical walls 64 and 65 and triangularly arranged end walls 66 and 67, Figures 2 and 6. The face 32 of the rotor is provided with a similar groove 68 concentric with the first. The stator faces 36 and 37 are provided with grooves 69 and 70, exactly like the rotor grooves 63 and 68 and registering with the latter, respectively. Disposed in the grooves 63 and 69 is an endless sealing ring 71 of bronze or other suitable material, this ring having a width equal to the combined width of the cylindrical portions of the two grooves. The angularly related outer walls of the grooves serve to center the ring, and, with the latter, define annular chambers 72 and 73 at the sides of the ring. A closed ring 71' is similarly disposed in the opposite grooves 68 and 70 with chambers at each side thereof.

The rings are fitted in the grooves with close tolerances, and when the pump is in operation the high pressure acts to decrease the tolerances

at the far sides of the rings. Leakage of liquid past the rings is reduced to a minimum by wire-drawing between the faces of the rotor and stator, also between the rings and the groove walls, for example, the ring 71 and wall 64, Figure 6. Upon reaching the triangular spaces as at 72 the volume of liquid is increased materially, thus reducing the velocity and pressure in these spaces. The liquid is again wiredrawn between the sealing rings and the groove walls, for example, the ring 71 and wall 65, Figure 6. Due to these factors, the floating rings provide a nearly perfect seal with a corresponding enhancement of pump efficiency. The rings retain their efficiency for a long period of use, but when worn, can be easily replaced by the ordinary mechanic.

In Figure 2 the rotor is shown as provided with openings 74 and 75 for pressure equalization. The casing has a drainage plug 76 and the cap a drainage plug 77.

In Figure 7 the ring 71 is the same as before, as are the cylindrical walls 78 and 79 of the grooves. However, instead of having angularly related end walls, as at 66 and 67, Figure 6, the grooves have arcuate end walls, as at 80, which serve as before to center the rings so that annular chambers are provided at the sides thereof.

In Figure 8, the groove walls, as at 81 and 82, are cylindrical throughout and have flat end walls, as at 83. The ring 84 is centered by the heads of screws 85 and 86 threaded in the sides thereof, or similar spacing means, such as pins or lugs, see also Figure 9.

In Figure 10 the grooves have cylindrical wall portions 87 and 88 and outward reduced extensions, as at 89, which provide positioning shoulders as at 90 and 91.

While we have shown two sealing rings, one at each side of the raceway, the provision of one only, particularly outwardly of the raceway, will add materially to the efficiency of the pump. On the other hand, more than one ring can be provided at either or both sides of the raceway, and it will be understood that other variations in the form and arrangement of parts are possible in the practice of the invention and are contemplated under the claims which follow.

We claim:

1. In apparatus comprising a rotor portion having a series of blades arranged on a circle whose center is on the axis of said rotor portion and having an annular lateral face concentric with said circle, a stator portion having a lateral face opposed to the face of said rotor portion, the improvement which comprises opposed circular grooves provided in said faces concentric with said circle, a floating sealing ring extending laterally into both of said grooves, the combined width of said grooves being greater than the width of said ring, and means positioning the ring so that an annular chamber is provided at each side of the ring.
2. Structure according to claim 1 wherein the grooves are shaped so as to constitute the positioning means.
3. Structure according to claim 1 wherein the positioning means is constituted by spacers carried by the ring.
4. In apparatus comprising a rotor portion having a lateral series of blades arranged on a circle whose center is on the axis of said rotor portion and having annular lateral faces inwardly and outwardly of said circle concentric therewith, a stator portion having a raceway opposed to said impellers and having faces inwardly and outwardly of said raceway opposed to the inner and outer rotor portion faces respectively, the improvement which comprises a set of opposed circular grooves provided in the opposed inner faces of the rotor and stator portions concentric with said circle, a set of opposed circular grooves provided in the opposed outer faces of the rotor and stator portions concentric with the first set, floating sealing rings in said sets of grooves, each of said rings extending laterally into both grooves of the set with which it is associated, the grooves of each set having a combined width greater than the width of the ring therein, and means positioning each ring so that an annular chamber is provided at each side thereof.
